GAME DEVICE OR THE LIKE

Alfred E. Ischinger, 410 Kenhorst Blvd.,
Reading, Pa. 19602

Filed July 21, 1967, Ser. No. 7,935

Term of patent 14 years

(Cl. D34—5)

FIG. 1.

FIG. 2.

FIG. 3.

FIG. 4.

FIG. 5.

FIG. 6.

FIG. 7.

FIGURE 1 is a face view of a game device or the like showing my new design it being understood that the pointer emanating from the center is movable to different selective positions;

FIG. 2 is a rear view thereof;

FIG. 3 is a sectional view thereof as seen by looking in the direction of the arrows 3-3 on FIG. 1;

FIG. 4 is an edge view, as seen by looking at FIG. 1 from the left;

FIG. 5 is an edge view, as seen by looking at FIG. 1 from the bottom;

FIG. 6 is a face view of the entire rotatable disc shown partially in FIG. 1.

FIG. 7 is a cross-sectional view taken as indicated by the arrows 7-7 on FIG. 6.

The dominant features of my design reside in the portions shown in full lines.

I claim:

The ornamental design for a game device or the like, substantially as shown and described.
